United States Patent Office

Des. 203,458

Patented Jan. 11, 1966

203,458

PLATE OR SIMILAR ARTICLE

Donna M. Miska, Corning, N.Y., assignor to Corning Glass Works, Corning, N.Y., a corporation of New York

Filed Mar. 29, 1965, Ser. No. 84,481

Term of patent 14 years

(Cl. D44—15)

The figure is a top plan view of a plate of conventional configuration showing my new design.

I claim:

The ornamental design for a plate or similar article, as shown and described.
